FABRIC FOLDING AND MARKING
MACHINE

John M. Biddle, Chicago, Ill., assignor to Union
Special Machine Company, Chicago, Ill., a cor-
poration of Illinois

Application October 4, 1932, Serial No. 636,249

3 Claims. (Cl. 223—38)

The invention relates to new and useful im-
provements in a machine for folding and shap-
ing a fabric section, and more particularly to
marking devices which are associated with the
fold forming devices.

An object of the invention is to provide a ma-
chine of the above type wherein the marking
devices may be adjusted when the folding ele-
ments of the machine are adjusted for producing
folded articles of different dimensions so that
predetermined relation between the markings
and the folds in the fabric may be maintained.

In the drawings which show by way of illus-
tration one embodiment of the invention—

Figure 1 is a plan view of a portion of a fold-
ing machine embodying the improvements;

Fig. 2 is a plan view of the shaping die plates
over which the fabric section is folded;

Fig. 3 is a plan view of the bed plate of the
folding machine on which the fabric is placed for
folding;

Fig. 4 is a sectional view on the line 4—4 of
Fig. 1;

Fig. 5 is a view showing the garment to which
the marked collar band has been attached and
also to which collar band the collar has been
attached;

Fig. 6 is a view showing the collar band folded
on the machine and the marking of the same,
and

Fig. 7 is a view showing more or less diagram-
matically the folding of the fabric edge about
the shaping die.

The folding machine includes a bed plate 1
of the usual construction, and a shaping die
which is preferably made in three sections, a
central section 2, an end section 3, and an end
section 4. These sections are attached to a sup-
porting head 5 by suitable bolts 6, 6. The bolts
6 passing through the supporting head and
threaded into the sections 3 and 4 extend through
slots 7 in the head, so that these sections 3 and
4 may be shifted endwise toward and from the
center of the head. This is for the purpose of
changing the dimensions of the collar band
which is to be formed. A fabric blank is indi-
cated at F in broken lines in Fig. 1. The fabric
blank is placed on the supporting bed plate.
The shaping die is then brought down into con-
tact with the fabric blank, folder blades 8, (see
Fig. 7) are moved in for the purpose of folding
the edge portions f of the fabric section over
on to the die shaping plate. This is the usual
method of folding the fabric section and shap-
ing the same. The folds are fixed in the usual

manner, and then the fabric section is removed
and it is ready to be stitched to other fabric
sections in the forming of the garment.

In the forming of a shirt, the collar band is
attached to the body of the shirt in a definite
relation thereto. In Fig. 6 of the drawings, the
neck portion of a shirt is shown. The shirt in-
cludes a body portion 9 having shoulder seams,
one of which is indicated at 10. The collar band
which is attached to the shirt is indicated at 11, 10
and the collar which is attached to the collar
band is indicated at 12. The collar band ex-
tends all the way from one edge portion of the
body of the shirt to the other. Shirts are usually
made in sizes varying a unit length, preferably 15
one-half inch. When the neck of a shirt is in-
creased by one-half inch, the collar band, of
course, must be increased a similar length. This
is the purpose of adjusting the shaping die, so
that collar bands may be folded and shaped by 20
the proper length for a given size shirt. When
the shirt increases in size, the distance between
the shoulder seams will increase, but only half
the distance of the increase in length of the col-
lar band. In other words, when the shirt and 25
collar band at the neck are increased by the
distance of one-half inch, the distance between
the shoulder seams is increased by one-fourth
inch. In order to aid the operator in stitching
the collar band to the body of the shirt, the 30
collar band is provided with a mark 13 which
has a predetermined relation relative to the
length of the collar band, so that if this mark
is placed at the proper shoulder seam, the collar
band will be properly located relative to the neck 35
of the garment. The collar band is also pro-
vided with a mark 14 at each end thereof, which
mark is placed at a predetermined distance from
the end of the collar band. The collar attached
to the collar band is always attached thereto at 40
a predetermined distance from the end of the
collar band, regardless of the size of the shirt.
If this mark 14, therefore, regardless of the size
of the collar band, is placed a predetermined dis-
tance from the end of the collar band, it may 45
be used for locating the collar relative to the
collar band for the stitching of the same to the
collar band.

The present invention has to do particularly
with the means for marking the collar band at 50
the places indicated above. The central section
of the shaping die 2 maintains a fixed relation
to the supporting head 5 for all sizes of collar
bands. On the under face of the central section
2 of the shaping die is a downwardly extending 55

lug 15 which, when contacting with the fabric section, will force the fabric section downward into the recess 16 in the supporting bed plate 4. This will indent the fabric and form a substantially permanent marking of the collar band at the center of each collar band.

The section 3 of the shaping die is provided with a downwardly projecting lug 17 which is located a fixed distance from the end of the shaping die. This lug will indent the fabric section, forcing the same downward into one of the recesses 18 formed in the supporting bed plate. The supporting bed plate has a series of recesses 18 which are of a unit distance apart, depending upon the variation in the size between garments. If the variation is one-half inch, then the distance between these openings will be one-fourth inch, for the reason that the length of the collar band from the center thereof will be increased one-fourth inch at each end, thus making up the half inch increase in the size of the garment. The section 4 of the die shaping member is provided on its under face with a depending lug 19 which is adapted to enter a recess 20 in the supporting bed plate, indenting the fabric and forming a substantially permanent marking in the fabric. There are, of course, a series of these recesses 20 which are likewise spaced a unit length, that is, one-fourth of an inch. These lugs mark the collar band at the points 14, 14, and the markings are of a uniform distance from the ends of the collar band, and a varying distance apart, according to the size of the shirt and the collar which is to be attached thereto. The marking devices have a maintained or predetermined distance relative to the folds formed in the fabric sections which shape and form the collar band. The bed plate is provided with a groove or recess 21 in which is located a bar 22. The groove at the sides 23 is undercut, and the bar is shaped so as to conform to this undercut. The bar is flush with the plate. Extending alongside of the bar is a clamping plate 24 which has the edge thereof adjacent the bar 22 undercut, thus producing a dove-tailed recess in which the bar is located. A plate 24 is secured by screws 25, 25 to the bed plate, and upon loosening the screws, the bar may be shifted in an endwise direction in the groove or recess 21. The bar 22 is located beneath the section 3 of the shaping die. There is a bar 22^a of similar construction, and clamped in position by a clamping plate 24^a located beneath the section 4 of the shaping die. Attached to this bar 22 is an upstanding lug 26. The section 3 of the shaping die is provided with a series of openings or recesses 27. The bar is positioned so that the lug is beneath one of these recesses, and when the die shaping member is brought down on to the fabric, the fabric will be pressed up into the opening or recess, and indented, thus producing a mark sufficiently permanent to aid in the placing of the collar band during the subsequent stitching operation. There are a series of openings or recesses 27, and these openings are placed a unit distance apart, which distance is half the distance between the recesses 18. If the recesses 18 are one-fourth inch apart, then the recesses 27 will be one-eighth inch apart, for the reason that when the garment is increased in size by one-half inch, the increased distance between the shoulder seams is one-fourth of an inch, and the increased distance of the shoulder seam from the center of the garment is one-eighth of an inch. The bar 22^a is likewise provided with a lug 26^a and the section

4 of the shaping die is provided with a series of openings or recesses 27^a. These recesses are spaced the same distance as the recesses 27 and the lug 26^a operates in precisely the same manner to indent or mark the garment at the other shoulder seam.

In the adjusting of the machine for a different size collar band, the bolts 6 are loosened and the sections 3 and 4 shifted a unit length and then again secured to the head 5. This adjustment will bring the lug carried by the sections of the shaping die into proper register with one of the recesses 18 at one end of the bed plate and one of the recesses 20 at the other end of the bed plate, respectively. The bars 22 and 22^a are then released and positioned so that the lugs thereon will engage, respectively, the proper recesses in the sections of the shaping die. This is all the adjustments that are necessary for the forming and marking of a collar band of a different size. The markings 14 on the collar band as noted above, will be a uniform distance from the end of the collar band for all sizes of garments. The markings 13 on the collar band will be properly formed so that said markings when the collar band is properly attached to the garment, will be located at the shoulder seams.

The lugs for marking or indenting the fabric may be made in any desired way. As shown in the drawings, the lugs on the bars are in the form of a wire staple fixedly attached to the bar, and the lugs in the sections of the shaping die are formed by bending the metal. It will be understood that any other suitable means may be used in place of lugs and recesses for marking the fabric sections. The essential feature consists in marking the fabric section with a mark which is sufficiently permanent to be maintained in the fabric section until after the shaped fabric section is stitched to the garment. It is essential also that the marking means shall be of a character that it can be readily adjusted when the shaping die is adjusted for the production of folded fabric sections of different sizes, so that the marking of the fabric section will always be in a predetermined relation to the folds in the fabric section regardless of the size or shape of the folded fabric section produced.

After the collar band is stitched to the garment, the mark 13 adjacent the right-hand end of the collar band as viewed in Fig. 5, and also adjacent the button end of the collar band, is placed in register with the shoulder seam 10. The button is indicated at 28. The collar band is placed in the machine with the button facing upward and with the body of the garment at the left of the needle. The line of stitching starts at the end 29 of the collar band, and the stitching proceeds along the line 30, thus joining the collar band to the body of the garment. By the placing of this mark 13 in register with the shoulder seam, the end of the collar band will be properly placed relative to the right-hand side of the body portion as viewed in this figure. The line of stitching will continue to the opposite end of the collar band, and the mark 13 at the opposite side of the collar band from the mark 13 shown in the drawings will automatically register with the shoulder seam. The garment is then turned and the collar 12 placed with the edge 12^a at the opposite side thereof from that shown in the drawings in register with the mark 14, and the line of stitching 31 produced, thus joining the collar to the collar band. This will automatically bring the edge 12^a as shown in the drawings, into

proper register with the mark 14. Thus it is that the markings made by the collar band may be used for placing the collar band relative to the body of the garment for stitching, and the markings on the collar band may also be used for the placing of the collar for stitching. This greatly facilitates the stitching of the collar band and the collar to the body of the garment, and insures a perfect location and register of the body of the garment, the collar band and the collar. Furthermore, the stitching begins at the button end of the collar band, and ends at the button end of the collar band, and therefore, will be concealed by the lapping end of the collar band containing the button hole.

Having thus described the invention, what I claim as new and desire to secure by Letters Patent, is—

1. A collar band folding and marking machine comprising a bed plate, a shaping die, means cooperating therewith for holding a fabric section over said die to form a shaped collar band, said shaping die having shiftable end sections for varying the length of the collar band, and a shiftable bar beneath each end section having an upwardly projecting lug, each end section having a series of openings therein a unit distance apart adapted to cooperate with said lugs in the marking of the fabric section.
2. A collar band folding and marking machine comprising a bed plate having a series of recesses therein, a shaping die having a series of openings or recesses therein, means cooperating therewith for folding a fabric section over said die to form a shaped collar band, said shaping die having

shiftable end sections for varying the length of the collar band, a shiftable bar carried by the bed plate beneath each end section of the shaping die, each bar having an upwardly projecting lug adapted to engage one of said openings or recesses in the section of the shaping die, and each shaping die having a downwardly projecting lug adjacent the end thereof adapted to engage one of said recesses in the bed plate.

3. A collar band folding and marking machine comprising a bed plate having a series of recesses therein, a shaping die having a series of openings or recesses therein, means cooperating therewith for folding a fabric section over said die to form a shaped collar band, said shaping die having shiftable end sections for varying the length of the collar band, a shiftable bar carried by the bed plate beneath each end section of the shaping die, each bar having an upwardly projecting lug adapted to engage one of said openings or recesses in the section of the shaping die, and each shaping die having a downwardly projecting lug adjacent the end thereof adapted to engage one of the recesses in the bed plate, said bed having a series of recesses spaced the same unit length as the unit length of adjustment of the sections of the shaping die, and each section of the die having a series of openings of one-half the unit length distance apart of the unit length adjustment of the die, whereby the collar band regardless of its size may be marked a uniform distance from the end thereof and also marked at points in register with the shoulder seams of the body of the garment to which it is to be attached.

JOHN M. BIDDLE. 35
